(57) **CLAIM**

The ornamental design for a seal for faucet aerator, as shown and described.

DESCRIPTION

FIG. 1 is a top, front, left perspective view of the seal for a faucet aerator in accordance with my design;

FIG. 2 is a bottom, rear, left perspective view thereof;

FIG. 3 is a front elevational view thereof;

FIG. 4 is a rear elevational view thereof;

FIG. 5 is a left side elevational view thereof, with the right side elevational view being a mirror image thereof;

FIG. 6 is a top plan view thereof; and,

FIG. 7 is a bottom view thereof.

The broken lines illustrated form no part of the claimed design of the seal for faucet aerator.
